UNITED STATES PATENT OFFICE.

EDGAR W. HEISEY, OF NEWARK, OHIO, ASSIGNOR TO A. H. HEISEY & CO., OF NEWARK, OHIO, A COPARTNERSHIP.

DESIGN FOR A GLASS VESSEL.

45,044.

Specification for Design.

Patented Dec. 16, 1913.

Application filed April 9, 1913. Serial No. 760,042. Term of patent 14 years.

To all whom it may concern:

Be it known that I, EDGAR W. HEISEY, a citizen of the United States, residing at Newark, county of Licking, State of Ohio, have invented a new, original, and ornamental Design for a Glass Vessel, of which the following is a specification, reference being had to the accompanying drawing, forming part thereof.

The figure is a perspective view of a glass vessel, showing my new design embodied thereon.

The design consists in the flat, horseshoe shaped portion *a* with the panel portion *b* which is raised above the horseshoe portion *a*, and which fills in the space bounded by said horseshoe portion.

I claim:

The ornamental design for a glass vessel, as shown and described.
